(57) **CLAIM**

The ornamental design for a remote control device with an icon, as shown and described.

DESCRIPTION

FIG. 1 is a front plan view of a remote control device with an icon; and,

FIG. 2 is an enlarged view of a portion of the remote control device with an icon.

The claimed design is flat and with all elements coplanar. The solid lines and areas within them form the entirety of the design. The broken lines represent portions of the remote control device with an icon that form no part of the claimed design.
